(57) **CLAIM**

The ornamental design for an anchor brace for lid, as shown and described.

DESCRIPTION

FIG. 1 is a top, rear perspective view of an anchor brace for lid;

FIG. 2 is a bottom, rear perspective view thereof;

FIG. 3 is a top, front perspective view thereof;

FIG. 4 is a bottom, front perspective view thereof;

FIG. 5 is a front side view thereof;

FIG. 6 is a rear side view thereof;

FIG. 7 is a right side view thereof;

FIG. 8 is a left side view thereof;

FIG. 9 is a top view thereof;

FIG. 10 is a bottom view thereof; and,

FIG. 11 is a sectional view taken along the lines “11-11” as shown in FIG. 9.

The broken lines shown in the drawings represent boundaries of unclaimed subject matter and form no part of the claimed design.
